UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

DRILLING TOOL.

Application filed October 2, 1925. Serial No. 60,076.

This invention relates to hand held drilling tools and more particularly to hand held drilling tools of the rotary type especially adapted to use with coal mining machines in drilling "shot" holes in the coal after the kerf has been cut therein preparatory to the "shooting" of the coal from the "solid".

In coal mining it is desirable to drill a series of "shot" holes in the coal subsequent to the cutting of a kerf in the face of the coal by the coal cutting machine and preparatory to the "shooting" of the coal from the "solid". Usually the drilling tools for drilling these "shot" holes are driven independently of the mining machine thereby greatly increasing the initial cost by the necessity of laying out separate power connections to both the drill and the mining machine. Usually such drilling tools are self-contained units held by the operator during operation thereof and driven by separate air or electric motors and are necessarily cumbersome and unwieldy to operate due to the inherent weight of such motors and their related parts.

A primary object of this invention is to provide a drilling tool especially adapted to use in drilling "shot" holes in the coal and which is driven directly from the mining machine driving motor thereby substantially decreasing the cost, weight, and size of the tool while still permitting a tool having the necessary power to be obtained. Another object of this invention is to provide an improved rotary drilling tool freely movable bodily in any direction with respect to its source of power and especially adapted to use in drilling "shot" holes in the coal and which is of an exceedingly inexpensive, simple, and compact character. Still another object of this invention is to provide an improved hand held drilling tool having improved and simplified controlling and driving means therefor. Yet another object of this invention is to provide an improved drilling tool having improved flexible transmission means between the same and the source of power. These and other objects will, however, subsequently more fully appear.

This invention in one of its aspects may comprise a drilling tool deriving its power

through the transmission gearing for the cutting mechanism of a coal mining machine with which the drilling tool cooperates in winning the coal from its natural bed. More specifically this invention may comprise a rotary drilling tool having a power shaft connected in a socket formed in one of the transmission gears for the cutting mechanism of a mining machine and this shaft preferably drives, through bevel gears and a manually operable jaw clutch and ratchet device carried within a swivel connection on the mining machine, a flexible transmission shaft herein preferably in the form of a wire rope or cable housed within a suitable metallic armor or covering. This shaft preferably drives the cutting tool through frictionally controlled spur gears rotatable on parallel axes and housed within the casing of the tool. Laterally projecting handles are preferably provided on the casing of the drilling tool to enable the operator to handle the same with facility.

In the accompanying drawings I have shown for purposes of illustration three forms which my invention may assume in practice.

In these drawings,—

Fig. 1 is a fragmentary side elevation of a coal cutting machine with which my improved drilling tool is associated.

Fig. 2 is a diagrammatic view illustrating the operation of the improved drilling tool in a mine.

Fig. 3 is a central longitudinal sectional view through the improved drilling tool and a portion of the improved transmission means therefor.

Fig. 4 is a rear end elevational view of the improved drilling tool taken substantially on line 4—4 of Fig. 3, the transmission shaft being shown in section.

Fig. 5 is a detail view of the driving ratchet.

Fig. 6 is a view similar to that shown in Fig. 3 illustrating a somewhat modified form of drilling tool.

Fig. 7 is a transverse vertical section taken substantially on line 7—7 of Fig. 6.

Fig. 8 is a central longitudinal sectional view of a further modified form of drilling tool.

In the illustrative construction shown in

Figs. 1 to 5 I have shown a drilling tool of improved form generally designated 1 operatively connected through a flexible transmission element 2 to a mining machine generally designated 3. The mining machine 3 may assume various forms, but for the purposes of illustration I have shown a mining machine of the type described in my copending application Serial No. 6,477, filed 10 Feb. 2, 1925. As the structure of this machine does not specifically enter into my invention detailed description of the same is deemed unnecessary other than to state that a shaft 4 of a reversible motor, not shown, 15 is provided which drives through transmission means to be hereinafter described a usual driving sprocket 5 which cooperates with the usual cutter bit carrying cutter chain 6 to drive the latter in a well known manner. As illustrated, the motor shaft 4 is adapted to have connected thereto by means of a manually operable gear clutch 7 a bevel pinion 8 which is meshed with and drives a larger bevel gear 9 rotatable on an axis perpendicular to the axis of the motor shaft and the gear 9 is journaled within suitably spaced ball bearings 10 carried within the machine frame. The bevel gear 9 has formed 20 thereon a spur pinion 11 which meshes with and drives a large spur gear 12 journaled on bearings 13 carried by the machine frame. As shown, the gear 12 is adapted to drive through a manually operable gear clutch 14, as is clearly described in my copending application mentioned above, a cutter chain driving shaft 15, the latter being journaled at its opposite ends within ball bearings 16 carried by the machine 25 frame. This shaft 15 has keyed thereto, as at 17 the cutter chain driving sprocket 5. From the foregoing description it will be clearly evident that when the clutches 7 and 14 are connected the cutter chain driving 30 sprocket 5 is adapted to be driven from the mining machine driving motor and that this driving sprocket may be disconnected from the transmission gearing 8, 9, 11, and 12 at will by means of the clutch 14.

Referring more particularly to my improved drilling tool and driving connections therefor, it will be observed that secured by a key 18 within a vertical socket or bore 19 formed within the shaft supporting the 35 gears 9 and 11 is a driving element 20 having a bore 21 extending through a substantial portion of its length. As shown, the upper end of the element 20 is provided with diametrically opposite vertical slots 22 which are adapted to receive the ends of a transversely disposed pin 23 suitably secured within a transmission shaft 24 having at its lower end a central opening or recess 25. Disposed within the bore 21 in the element 20 and the opening 25 in the shaft 24

is a coiled compression spring 26 which normally tends to force the members 20 and 24 apart. The upper end of the shaft 24 is provided with a lateral circular flange 24^a having formed on the upper surface thereof 70 ratchet teeth 27 which are adapted to cooperate with corresponding ratchet teeth 28 formed on an annular depending flange 29 carried at the lower end of a bevel gear 30. As shown, the bevel gear 30 is provided with 75 an upstanding sleeve portion 31 suitably journaled in a bearing sleeve 32 carried within a bore 33 formed in a casing or housing member 34. In this instance the bevel gear 30 is held against inward axial movement 80 by means of a radially expanding split ring 35 which engages an annular bearing member 36 supported by the upper flange 37 of the bearing sleeve 32 and disposed in a bore 38 formed in the upper end of 85 the casing member 34. As shown, the bore 38 is closed by a suitable head or cap member 39 held in position with respect to the casing 34 by means of cap screws 40. Herein it will be observed that 90 the casing member 34 is rotatably mounted or swiveled within a bore 41 formed within a detachable supporting member 42 secured as by screws 43 to the frame of the mining machine, the member 42 also having a depending sleeve portion 44 which forms a support for the upper bearing 10. The inner periphery of the member 42 is circumferentially grooved or recessed at 45 and with this groove radially located pins 46 100 carried by the casing member 34 cooperate to prevent axial displacement of the latter member from the bore 41 while still permitting free rotatable movement thereof. In accordance with this invention a manually adjustable element 47 is provided which 105 threadedly engages a thread opening 47^a formed in the closure member 39 and this member 47 projects inwardly within the hollow sleeve portion 31 of the gear 30 and 110 into engagement with a ball thrust bearing 48. The ball bearing 48 is disposed between the member 47 and a member 49 slidably mounted in the bore of the sleeve 31 and having at its lower end a suitable recess 115 50 within which a suitable ball thrust bearing 51 is disposed, the latter engaging the upper surface of the lateral flange 24^a formed on the shaft 24. It will thus be evident that when the member 47 is suitably 120 adjusted the member 49 is thrust axially, compressing the spring 26 and forcing the ratchet teeth 27, 28 formed on the members 24 and 30, respectively, apart, consequently disconnecting the drive therebetween, the 125 pin 23 sliding in the vertical slots 22 in the member 20 at that time. Meshed with the bevel gear 30 is a similar bevel gear 52 threadedly secured as at 53 to a member 54, the latter being journaled in a bearing sleeve 130

55 disposed within a bore 56 disposed at right angles to the bore 33 and formed in a laterally projecting portion or boss on the casing member 34. As shown, the member 54 is provided with a recess 57 within which one end of a flexible transmission element 58, herein shown in the form of a wire rope or cable, is suitably rigidly secured, preferably by brazing. The opposite end of the wire rope 58 is likewise rigidly secured within a recess 59 formed within one end of a rotatable transmission member 60, splined, as at 61, in operative sliding relation with a spur pinion 62, the latter having laterally 10 extending hub portions suitably journaled in spaced bearing sleeves 63 suitably carried by the casing or housing 64 of my improved drilling tool. It will herein be observed that disposed between the casing 34 and casing 64 and through which the wire rope 58 extends is a tubular metallic armor or covering element 65 preferably of flexible jointed structure. The ends of the member 65 project within split clamping elements 66 having external tapered surfaces 67 which cooperate with corresponding internal tapered surfaces formed in rotatable clamping members 68 threadedly connected at 69 to the casings 34 and 64, respectively. 15

20 In accordance with this invention the casing 64 is preferably composed of two main parts 70 and 71 held together by means of cap screws 72, the member 70 being detachable to permit the assembling or disassembling 25 of the drill parts with facility. As shown, the spur pinion 62 is meshed with a larger spur gear 73 having a hub portion 74 journaled on an axis parallel with the axis of the pinion 62 in a bearing sleeve 75, keyed as at 76 to the detachable casing member 70. Carried by the spur gear 73 is a series of clutch plates 77 which are interleaved with a series of clutch plates 78 carried by a clutch member 79 keyed as at 80 to a shaft 30 35 disposed coaxially with the gear 73. The shaft 81 is journaled in a bearing sleeve 82 carried by the casing member 70 and a bearing sleeve 83 carried by a detachable cover plate 84 suitably secured to the rear end of the casing member 71. As illustrated, the rear end of the shaft 81 has threadedly connected thereto, as at 85, an adjustable member 86 which is adapted to adjust the tension of a coiled spring 87 encircling the shaft 40 45 of the casing 34 the drilling tool 1 may be located in any desired position with respect to the mining machine. It will herein be noted that the ratchet teeth 27, 28 automatically prevent reverse drive of the bevel gears 30 and 52 upon reversal of the driving motor, consequently preventing the uncoiling and resultant damaging of the wire rope 53 and its related parts.

10 In the form of my invention shown in Figs. 6 and 7 it will be observed that the transmission connections for the rear end of the flexible transmission element 58 are substantially identical to those described above 15 while the forward end of the element 58 is suitably rigidly secured, preferably by brazing, within a recess formed within the rear end of a transmission member 103 splined as at 104 in operative sliding relation with 20 a spur pinion 105. Herein the pinion 105 is provided with a rearwardly projecting sleeve portion 106 journaled within a concentric sleeve portion 107 formed on a spider member 108 which has suitably secured 25 thereto stub shafts 109 which form supports for a plurality of planetary gears 110 meshing with the spur pinion 105 and with a large internal gear 111. As shown, the gear 111 is provided with a forwardly projecting hub portion 112 disposed coaxially with the pinion 105 and journaled within bearing sleeves 113, 113^a carried by the drill casing 114. Furthermore, it will be observed that the hub portion 112 is provided 30 at its front end with a tapered socket 115 within which the shank of an auger drilling tool 116 is adapted to be secured. In accordance with this invention the spider member 108 is provided with an outwardly extending circular flange 117, the opposite sides of which are engaged by friction rings 118. Threadedly connected to the casing 114 are bolts 119 encircled by coiled springs 120 disposed in recesses 120^a formed within 35 a pressure applying member 121, the latter having a rearwardly located reduced threaded portion 122 with which a manually operable adjustable member 123 is secured. As shown the member 121 is adapted to engage 40 pins 124 which extend through suitable apertures in the casing 114 and into engagement with the rear friction ring 118. As shown, secured to the opposite sides of 45 the casing 114 are laterally projecting 50 grasping handles 101^a.

In the use of this form of my invention it will be assumed that the ratchet teeth 27, 28 are connected and the flexible transmission element 58 is rotating. The operator then 55 manipulates the adjusting member 123, releasing the tension on the springs 120, causing the latter to force the member 121 and the pins 124 into engagement with the friction rings, consequently preventing the

spider member 108 from rotating relative to 65 the casing 114. When this spider member 108 is held stationary power is transmitted from the transmission element 103, spur pinion 105, planetary gears 110, internal gear 111, to the cutting bit 116. If it is 70 desired to stop operation of the cutting tool the operator manipulates the member 123 in a reverse manner and the springs 120 are compressed, releasing the spider member 75 108 and permitting the latter to freely rotate, thus causing the bit to remain stationary.

In the form of my invention shown in Fig. 8 it will be observed that the flexible transmission element 58^a is coiled in a reverse manner from that shown in Figs. 3 and 6 while planetary pinions 125 are journaled on bearing sleeves 126 carried by stub shafts 127 disposed parallel with the axis of the pinion 5 and these shafts are carried by a 80 spider member 128. The member 128 has a forwardly projecting cylindrical hub portion 129 suitably journaled in spaced bearing sleeves 130 and 130^a carried by the casing 90 114 of the drilling tool. The forward extension of the spider member 128 is provided with a tapered socket 115^a which receives the shank of an auger cutting tool 116^a. In this instance the internal gear 111^a is provided with an outwardly extending circular 95 flange 131 with which the friction rings 118^a are adapted to cooperate. Otherwise this form of my invention is substantially the same as described in Figs. 6 and 7.

In the use of this form of my invention 100 it will be observed that when the member 123 is manipulated, the friction rings 118^a are pressed together thus preventing rotation of the internal gear 111^a and causing the planetary gears to react thereon and to 105 rotate relative thereto in an orbit about the axis of the pinion 105, consequently causing the spider member 128 and the cutting tool 116^a to be rotated. With the exception that 110 the flexible power transmission element 58^a rotates in a direction opposite from that shown in Fig. 6 the operation of this form of my invention is substantially the same as that described above in connection with Fig. 6.

115 Other operations and advantages of my improved rotary drilling tool will be clearly apparent to those skilled in the art.

While I have in this application specifically described three forms which my invention may assume in practice, it will be understood that these forms of the same are shown for purposes of illustration and that the invention may be modified and embodied in various other forms without departing from its spirit or the scope of the appended claims.

120 125 What I claim as new and desire to secure by Letters Patent is;

1. In a drilling tool, a power driving element, cooperating gearing driven thereby, a flexible transmission shaft driven by said gearing, a swivel mounting for said flexible shaft coaxial with one of said gears, and a drilling tool driven by said flexible shaft.
2. In a drilling tool, a power driving element, cooperating gearing driven thereby, a flexible transmission shaft driven by said gearing, a transmission shaft driven by said flexible shaft, cooperating gearing driven by said second mentioned transmission shaft, a tool driving shaft, and a manually controllable clutch for connecting said tool driving shaft to said last mentioned gearing.
3. In a drilling tool, a power driving element, cooperating gearing driven thereby, a flexible transmission shaft driven by said gearing, a transmission shaft driven by said flexible shaft, cooperating gearing driven by said second mentioned transmission shaft, said latter shaft having a reciprocatory movement relative to one of said gears, and a drilling tool driven by said last mentioned gearing.
4. In a drilling tool, a power driving element, cooperating gearing driven thereby, a manually controllable clutch for connecting said gearing and said driving element, a flexible wire rope transmission shaft driven by said gearing, a transmission shaft driven by said flexible shaft, a tool driving shaft, and cooperating gearing for connecting said second mentioned transmission shaft to said tool driving shaft.
5. In a drilling tool, a power driving element, cooperating bevel gearing driven thereby, a manually controllable clutch connecting said driving element to said gearing, a flexible transmission shaft driven by said gearing, a transmission shaft driven by said flexible shaft, a tool driving shaft, and cooperating gearing connecting said two last mentioned shafts.
6. In a drilling tool, a power driving element, cooperating gearing driven thereby, a transmission shaft driven by said gearing, a flexible transmission shaft driven by said shaft, a transmission shaft driven by said flexible shaft, one of said shafts having a reciprocatory movement relative to another of said transmission shafts during rotation thereof, cooperating gearing driven by said third mentioned transmission shaft, and a drilling tool driven by said last mentioned gearing.
7. In a drilling tool, a power driving element adapted to be driven in opposite directions, cooperating gearing driven thereby, manually releasable mechanism connecting said gearing with said driving element, said mechanism being automatically operative to prevent driving of said gearing when said driving element is driven in one direction, a flexible transmission shaft driven by said
- gearing and adapted to rotate in only one direction, and a drilling tool driven by said flexible shaft.
8. In a drilling tool, a power driving element adapted to be driven in opposite directions, cooperating gearing driven thereby, manually releasable mechanism connecting said gearing with said driving element, said mechanism being automatically operative to prevent driving of said gearing when said driving element is driven in one direction, a flexible transmission shaft driven by said gearing and adapted to rotate in only one direction, a tool driving shaft, and cooperating gearing connecting said tool driving shaft with said flexible shaft.
9. In a drilling tool, a power driving element adapted to be driven in opposite directions, cooperating gearing driven thereby, manually releasable mechanism connecting said gearing with said driving element, said mechanism being automatically operative to prevent driving of said gearing when said driving element is driven in one direction, a transmission shaft driven by said gearing, a flexible transmission shaft driven by said shaft and adapted to rotate in only one direction, a transmission shaft driven by said flexible shaft, a tool driving shaft, and cooperating gearing connecting said third mentioned transmission shaft with said tool driving shaft, one of said shafts having reciprocatory movement relative to one of said latter gears during rotation thereof.
10. In a drilling tool, a power driving element adapted to be driven in opposite directions, cooperating gearing driven thereby, manually releasable mechanism connecting said gearing with said driving element, said mechanism being automatically operative to prevent driving of said gearing when said driving element is driven in one direction, a flexible transmission shaft driven by said gearing and adapted to rotate in only one direction, a tool driving shaft, gearing connecting said flexible shaft with said tool driving shaft, and a manually controllable clutch for connecting said last mentioned gearing to said tool driving shaft.
11. In a drilling tool, a power driving element, cooperating gearing driven thereby, a manually releasable ratchet mechanism connecting said gearing with said driving element, a flexible transmission shaft driven by said gearing, a transmission shaft driven by said flexible shaft, and a tool driven by said second mentioned transmission shaft.
12. In a drilling tool, a power driving element, cooperating gearing driven thereby, a ratchet mechanism for connecting said gearing with said driving element, manually operable means for releasing said ratchet mechanism, a flexible transmission shaft driven by said gearing, a transmission shaft driven by said flexible shaft, a tool driving shaft,

and means including a manually controllable clutch for connecting said two last mentioned shafts.

13. In a drilling tool, a power driving element, cooperating gearing driven thereby, a ratchet mechanism for connecting said gearing with said driving element, manually operable means for rendering said ratchet mechanism inoperative, a flexible transmission shaft driven by said gearing, a transmission shaft driven by said flexible shaft, a tool driving shaft, cooperating gearing connecting said two last mentioned shafts, and a manually controllable clutch for connecting said gearing to said tool driving shaft.

14. In a drilling tool, a power driving element, cooperating gearing driven thereby, a ratchet mechanism for connecting said gearing with said driving element, manually operable screw operated means for rendering said ratchet mechanism inoperative, a flexible transmission shaft driven by said gearing, and a drilling tool driven by said flexible shaft.

15. In a drilling tool, a power driving element, cooperating gearing driven thereby, a manually controllable clutch connecting said gearing with said driving element, a flexible transmission shaft driven by said gearing, a transmission shaft driven by said flexible shaft, cooperating gearing driven by said transmission shaft, said transmission shaft being connected in operative sliding relation with one of the gears of said last mentioned gearing, a tool driving shaft, and a manually controllable clutch connecting said last mentioned gearing with said tool driving shaft.

16. In a drilling tool, a power driving element rotatable in opposite directions, cooperating gearing driven thereby, a ratchet mechanism for connecting said gearing with said driving element, said ratchet mechanism being adapted to slip when said driving element is rotated in one direction, manually operable means for rendering said ratchet mechanism inoperative, a flexible transmission shaft driven by said gearing, and a drilling tool driven by said flexible shaft.

17. In a drilling tool, a power driving element rotatable in opposite directions, cooperating gearing driven thereby, a ratchet mechanism for connecting said gearing with said driving element, said ratchet mechanism being adapted to slip when said driving element is rotated in one direction, manually operable means for rendering said ratchet mechanism inoperative, a flexible transmission shaft driven by said gearing, and adapted to rotate in only one direction, a tool driving shaft, cooperating gearing driven by said transmission shaft, and a manually controllable clutch for connecting said last mentioned gearing to said tool driving shaft.

18. In a drilling tool, a power driving element rotatable in opposite directions, cooperating gearing driven thereby, a ratchet mechanism for connecting said gearing with said driving element, said ratchet mechanism being adapted to slip when said driving element is driven in one direction, resilient means for maintaining said ratchet mechanism in operative position, manually operable means for overcoming said resilient means to render said ratchet mechanism inoperative, a flexible transmission shaft driven by said gearing adapted to rotate in only one direction, cooperating gearing driven thereby, a tool driving shaft, and a manually operable clutch for connecting said last mentioned gearing to said tool driving shaft.

19. In a drilling tool, a power driving element, bevel gearing driven thereby, a ratchet mechanism for connecting said driving element with one of the gears of said gearing, said mechanism comprising cooperating ratchet elements, and a spring for forcing said elements together, manually operable means for separating said ratchet elements to render said ratchet mechanism inoperative, a flexible transmission shaft driven by said gearing, a transmission shaft driven by said flexible shaft, cooperating gearing driven thereby, a tool driving shaft, and a manually controllable friction clutch for connecting said last mentioned gearing to said tool driving shaft.

20. In a drilling tool, a power driving element rotatable in opposite directions, bevel gearing driven thereby, a ratchet mechanism for connecting said driving element with one of the gears of said gearing, said ratchet mechanism being adapted to slip when said driving element is rotated in one direction and comprising cooperating ratchet elements, and a spring for forcing said elements together, manually operable means for separating said ratchet elements to render said ratchet mechanism inoperative, a flexible transmission shaft driven by said gearing, a transmission shaft driven by said flexible shaft, a tool driving shaft, and means including a manually controllable friction clutch for connecting said two last mentioned shafts in driving relation.

21. In a drilling tool, a power driving element rotatable in opposite directions, bevel gearing driven thereby, a ratchet mechanism for connecting said driving element with one of the gears of said gearing, said ratchet mechanism being adapted to slip when said driving element is rotated in one direction and comprising cooperating ratchet elements, and a spring for forcing said elements together, manually operable means for separating said ratchet elements to render said ratchet mechanism inoperative, a flexible transmission shaft driven by said gearing.

- and adapted to rotate in only one direction, a transmission shaft driven by said flexible shaft, cooperating gearing driven by said last mentioned transmission shaft, a tool driving shaft, and a manually controllable friction clutch for connecting said last mentioned gearing to said tool driving shaft. 6
22. In a drilling tool, a power driving element, cooperating gearing driven thereby, a ratchet mechanism for connecting one of said gears with said driving element, said ratchet mechanism comprising cooperating ratchet elements, a spring for forcing said elements together, one of said elements rotating directly with one of said gears, a flexible transmission shaft driven by said gearing, and a tool driven by said flexible shaft. 10
24. In a drilling tool, a power driving element, cooperating gearing driven thereby, a ratchet mechanism for connecting one of said gears with said driving element, said ratchet mechanism comprising cooperating ratchet elements, and a spring for forcing said elements together, one of said ratchet elements rotating directly with one of said gears, means for rendering said ratchet mechanism inoperative including manually operable means for forcing said ratchet elements apart, a flexible transmission shaft driven by said gearing, a tool driving shaft, and means including a manually controllable friction clutch for connecting said flexible shaft in driving relation with said tool driving shaft. 20
25. In a drilling tool, a power driving element, cooperating gearing driven thereby, manually releasable mechanism connecting said gearing with said driving element, a flexible transmission shaft driven by said gearing, a reciprocable transmission element driven by said flexible shaft, a tool driving shaft, and means including a manually controllable clutch connecting said reciprocable transmission element in driving relation with said tool driving shaft. 40
25. In a drilling tool, a power driving element, cooperating gearing driven thereby, and gears of said gearing being rotatable on angularly related axes, a flexible transmission shaft driven by said gearing, a swivel mounting for said flexible shaft rotatable about the axis of one of said gears, and a drilling tool driven by said flexible shaft. 50
26. In a drilling tool, a power driving element, cooperating gearing driven thereby, the gears of said gearing being rotatable on angularly related axes, a flexible transmission shaft driven by said gearing, a swivel mounting for said flexible shaft rotatable about the axis of one of said gears, a transmission shaft driven by said flexible shaft, cooperating gearing driven by said second mentioned transmission shaft, a tool driving shaft, and a manually controllable clutch connecting said tool driving shaft with said last mentioned gearing. 65
27. In a drilling tool, a power driving element, a drill bit, and driving connections between said driving element and said bit including a flexible transmission shaft, and means including a manually controllable friction clutch between said flexible shaft and said drill bit. 70
28. In a drilling tool, a power driving element, a cutting bit, driving connections between said driving element and said bit including cooperating gearing, a flexible shaft, and a reciprocable transmission shaft driven by said flexible shaft and having operative 80 sliding connection with one of the gears of said gearing. 75
29. In a drilling tool, a motor, a power driving element rotatable thereby in opposite directions, a cutting bit, and power transmission means between said driving element and said bit including means for automatically rendering said transmission means inoperative upon rotation of said driving element in one direction and a flexible transmission element between said automatic means and said bit. 85
30. In a drilling tool, a power driving element rotatable in opposite directions, a cutting bit, and power transmission means between said driving element and bit including ratchet mechanism for automatically rendering said transmission means inoperative upon rotation of said driving element in one direction, and manually operable means 100 for releasing said ratchet mechanism at will operative to effect disengagement of the parts of the latter. 90
31. In a drilling tool, a power driving element, a cutting bit, and flexible transmission means between said driving element and said bit including a wire rope transmission shaft, and flexible housing means for said shaft. 105
32. In a drilling tool, a power driving element, a cutting bit, and flexible transmission means between said driving element and said bit including a wire rope transmission shaft, and flexible housing means for said element, a portion of said wire rope having 110 a reciprocatory movement during rotation thereof. 115
33. In a drilling tool, a frame, a power driving element carried thereby, a hole drilling device actuated by said driving element and connected to said frame by power transmitting means operative to effect rotation of said device on its axis in any position thereof and permitting translative movement of the drilling device bodily in any direction relative to said driving element, said means including elements having pivotal 120 connection with said frame. 125

34. In a drilling tool, a frame, a power driving element thereon, a drill bit, and flexible transmission means between said driving element and bit including a transmission shaft and a pivotal mounting for the inner end of said shaft on said frame about which said shaft may be moved with any angular position relative thereto, said bit being carried at the outer end of said shaft.
- 5 35. In a drilling tool, a power driving ele-
10 ment rotatable in opposite directions, a tool, and transmission means between said driving element and tool including a wire rope transmission element adapted to drive said tool in only one direction and mechanism automatically releasable upon rotation of said driving element in a reverse direction to prevent the uncoiling of the wire rope strands.

In testimony whereof I affix my signature.

MORRIS P. HOLMES.

15

CERTIFICATE OF CORRECTION.

Patent No. 1,667,156.

Granted April 24, 1928, to

MORRIS P. HOLMES.

It is hereby certified that error appears in the printed specification of the above numbered patent requiring correction as follows: Page 2, line 41, for the misspelled word "sproket" read "sprocket", line 99, for the word "at" first occurrence read "as", and line 107, for "thread" read "threaded"; page 3, line 123, for "thust" read "thrust"; page 5, line 97, claim 9, after the word "having" insert the article "a"; page 6, line 78, claim 18, after the word "gearing" insert the word "and"; same page, line 89, claim 19, for "rachet" read "ratchet"; page 7, lines 19 and 36, for claim numbers "24" and "25" read "23" and "24"; and that the said Letters Patent should be read with these corrections therein that the same may conform to the record of the case in the Patent Office.

Signed and sealed this 29th day of May, A. D. 1928.

(Seal)

M. J. Moore,
Acting Commissioner of Patents.

34. In a drilling tool, a frame, a power driving element thereon, a drill bit, and flexible transmission means between said driving element and bit including a transmission shaft and a pivotal mounting for the inner end of said shaft on said frame about which said shaft may be moved with any angular position relative thereto, said bit being carried at the outer end of said shaft.
- 5 35. In a drilling tool, a power driving ele-
10 ment rotatable in opposite directions, a tool, and transmission means between said driving element and tool including a wire rope transmission element adapted to drive said tool in only one direction and mechanism automatically releasable upon rotation of said driving element in a reverse direction to prevent the uncoiling of the wire rope strands.

In testimony whereof I affix my signature.
